US0D1101908S

(12) **United States Design Patent** (10) **Patent No.:** **US D1,101,908 S**
(45) **Date of Patent:** **** Nov. 11, 2025**

(54) **VACUUM SYSTEM PIPE FOR A SEWAGE UNIT**

(71) Applicant: **Jets AS**, Hareid (NO)

(72) Inventor: **Erlend Leonard Kvalsund**, Vigra (NO)

(73) Assignee: **Jets AS**, Hareid (NO)

(**) Term: **15 Years**

(21) Appl. No.: **35/519,548**

(22) Filed: **Oct. 26, 2023**

(80) **Hague Agreement Data**

Int. Filing Date: **Oct. 26, 2023**

Int. Reg. No.: **DM/233975**

Int. Reg. Date: **Oct. 26, 2023**

Int. Reg. Pub. Date: **Dec. 29, 2023**

(57) **CLAIM**

The ornamental design for a vacuum system pipe for a sewage unit as shown and described.

DESCRIPTION

The patent or application file contains at least one drawing executed in color. Copies of this patent or patent application publication with color drawing(s) will be provided by the Office upon request and payment of the necessary fee.

1. Vacuum system pipe for a sewage unit

1.1 : Right

1.2 : Left

1.3 : Front

1.4 : Back

1.5 : Top

1.6 : Bottom

1.7 : Perspective

The broken lines and yellow color overlays depict portions of the vacuum system pipe for a sewage unit that form no part of the claimed design.

1 Claim, 7 Drawing Sheets
